UNITED STATES PATENT OFFICE.

WARREN McARTHUR, JR., OF PHOENIX, ARIZONA.

AUTOMOBILE RADIATOR CONSTRUCTION.

Application filed July 16, 1924. Serial No. 726,236.

This invention relates in general to automobile radiator construction and more particularly to an improved construction and arrangement of the radiator core, shell and neck so that various types of radiator caps may be securely locked on said necks.

At the present time, the conventional radiator construction is to have a core or cooling section separate from and fastened 10 to an outer shell. The core is provided at its top with a neck, permanently fastened thereto, for the purpose of filling the core with a cooling medium. The usual method of fastening the core into the shell is by bolts or 15 other means so that should it become necessary to repair or replace the core, the core can be removed from the shell by removing the cap from the neck and unfastening the bolts so that the shell can be pulled outward- 20 ly from the bottom of the core and then raised upwardly until the top of the shell is lifted sufficiently high to clear the top of the neck which extends through an opening in the top of the shell.

25 In providing a theft-proof radiator neck cap, it has been necessary heretofore to incorporate in it some device that will facilitate the removal of the cap from the neck, when it becomes necessary to remove the shell for 30 purposes of repair or replacement of the core. The removal of these theft-proof radiator neck caps is at times a very inconvenient, tedious and difficult operation. With the present day type of radiator construction, these caps must be removed before 35 the shell can be lifted from the core because the caps are larger than the opening in the top of the shell and consequently will not pass through such opening.

40 Objects of the invention are the provision of a radiator constructed so that such theft-proof caps may be employed on the radiator necks and the core removed from the shell without removal of the cap from the neck; the provision of a radiator construction in 45 which the neck is detachable from the core and shell to permit removal of the core from the shell for purposes of repair or replacements; the arrangement of the parts in such a construction, so that the neck will be locked against removal while the parts are in assembled relation and permitting the removal of said neck only upon partial detachment of the shell from the core; and such other ob-

jects and advantages of the invention as may 55 be found to obtain in the structure herein-after set forth and claimed.

In the accompanying drawings, forming a 60 part of this specification, and showing for purposes of exemplification, a preferred form and manner in which the invention may be embodied and practiced, but without limiting the claimed invention specifically to such illustrative instance or instances:

Figure 1 is a front elevational view of an 65 automobile radiator embodying my invention.

Fig. 2 is a side elevational view of the same.

Fig. 3 is a top plan view of the radiator 70 neck and cap therefor.

Fig. 4 is a front elevational view, parts being shown in section, of the radiator neck and cap therefor.

Fig. 5 is a vertical cross-sectional view 75 taken on the line 5-5 of Fig. 4.

On the drawings, 10 is the radiator shell having upwardly extending sides 11 and a curved top 12. Brackets 13 having apertures 14 therein are provided at the lower portions of the sides 11 to secure the shell to similar brackets on the core. The top 12 of the shell is provided with an opening 15 and portions of material 15' about said opening are cut away to provide slots 16 in the shell which receive projections on the neck. The core or cooling section 17 is formed separate from the shell and is provided with brackets 18 at the lower portions of its sides, said brackets having apertures which register 85 with the apertures in the brackets 13 and through which means may pass to secure the core within the shell. The bottom 19 of the shell is provided with bolts 20 that also serve to keep the shell in proper position on the core. The top 21 of the core is provided with an aperture 22 and extending upwardly from this opening is an annular collar 23 which is permanently clinched at 24 to the material about the aperture 22 in the top 21. At its upper end the collar is threaded on its outer surface 25 to receive the threaded lower end 26 of the removable radiator neck 27 so that the neck can be removably secured on the core and in order to prevent possible leakage through the joint between the portions 25 and 26, there is provided at the lower end of the removable neck a gasket 28. The cy-

lindrical neck is provided with projections 29 that fit into the slots 16 when the shell is in normal assembled position, said projections having holes for the reception of the ends of a holding down bale 30. The projections 29 extend from the bottom of the neck to a point 31 short of the top of the neck so that when the ends of the bale 30 are withdrawn from the projections 29 and the shell is unfastened at the bottom and swung out, as indicated in dotted lines in Fig. 2, it can be raised over the core until the top of the shell clears the top of the projections, thereby releasing the neck from the shell with sufficient clearance to permit unscrewing of the neck from the collar. A filter opening cap 32 is hinged to the front 33 of the upper end of the neck, said cap having a curved slot 33' providing a cam surface upon which the bale 30 rides to hold the cap tightly down in the top of the neck to close the filler opening.

To assemble the radiator, the ends of the bale 30 are withdrawn from the projections 29 and the neck then inserted through the opening in the top of the shell until the top of the projections 29 is beneath the top of the shell, then the neck is screwed tightly down on the threaded end of the collar, then the shell is lowered so that the projections 29 extend into the slots 16 which prevents further rotation of the neck. After the shell is so assembled it is fastened to the core at its sides and bottom and the ends of the bale 30 are inserted in the openings in the projections 29. To remove the core from the shell, the ends of the bale 30 are pulled out of the projections 29 and the shell is detached from the bottoms and sides of the core and swung outwardly and then upwardly until the top of the shell clears the upper ends of the projections, then the neck is unscrewed from the collar 23. After the neck is unscrewed from the collar the neck can be lifted out of the shell and the shell lifted off of the core.

From the foregoing it will be noted that the shell can be removed from the core without removing the cap from the neck; that the neck cannot be unscrewed from the core while the shell is normally assembled onto the core; that an ornamental cap or other device can be locked or permanently secured to the neck and yet permit removal of the shell from the core; that the neck and its attached cap cannot be removed until after the shell is released from the bottom of the core and also released from the sides of the core, and to do this it is necessary to unfasten the securing means on the inside of the shell.

This invention as hereinabove set forth is embodied in a particular form of construction but may be variously embodied within the scope of the claims hereinafter made.

Those features of the invention exemplified in the foregoing description which relate more particularly to the locking of a

removable neck and a device extending from the upper part thereof in position by the shell when assembled on the core and to the removal of the neck and the device only when the shell is detached or partially removed from the core are made the subject matter of my copending application for Letters Patent of the United States, filed July 16, 1924, Serial No. 726,237.

70

75

I claim:

1. An automobile radiator construction comprising, in combination: a radiator core; a removable radiator shell therefor; said core having an aperture in its top; an annular collar rigidly clinched to the material about the aperture in said core top; said collar being threaded at its upper end; a radiator neck threaded at its lower end to removably engage the threaded end of said collar, said neck having projections on its outer surface; a cap for said neck; an annular gasket interposed between the lower end of said neck and said collar; said shell having an opening in its top through which said neck extends, portions of the material about said opening being cut away to receive the projections on said neck when said shell is in assembled position on said core.

80

85

90

2. An automobile radiator construction comprising, in combination: a radiator core; a radiator shell therefor and removable therefrom; said core having an aperture in its top; an annular collar rigidly clinched to the material about the aperture in said core top, said collar having screw threads thereon; a radiator neck screw threaded to removably engage the screw threaded end of said collar; said neck having projections on its outer surface; a cap for said neck; said shell having an opening in its top through which said neck extends; portions of the material about said opening being cut away to receive the projections on said neck when said shell is in assembled position on said core.

95

100

105

110

3. An automobile radiator construction comprising, in combination: a radiator core; a radiator shell, said core having an opening in its top; a collar permanently secured to the material about said opening; a neck removably secured to said collar, said neck having extensions thereon; said shell having an opening therein through which said neck extends, portions of said shell being cut away to enclose the extensions on said neck and preventing the removal of said neck when said shell, core and neck are in normal assembled relation.

115

120

125

4. A radiator construction comprising, in combination: a core; a shell therefor, said shell being removable from said core; a radiator neck removably secured on said core, said shell having an opening therein through which said neck extends, said neck and said shell being fashioned to interlock with each

130

other to prevent removal of said neck from said core when said shell is in normal assembled position on said core.

5. A radiator construction comprising, in combination: a core; a shell therefor; a neck removably connected to said core; a locking member on said neck directly cooperating with the shell whereby said neck is locked in position directly by said shell so long as 10 said shell is assembled on said core.

6. A radiator construction comprising, in combination: a core; a shell therefor; a neck removably connected to said core; means cooperating with said neck and said shell to connect said neck and said shell directly with each other to permit said neck to be locked in position directly by said shell.

7. An automobile radiator construction comprising, in combination: a core; a shell; 20 a neck removably connected to said core, said shell and said neck providing a slot and a projection; said projection fitting in said slot when said shell, neck and core are in assembled position and preventing removal of 25 the shell and neck while said projection is in said slot.

8. A radiator construction comprising, in combination: a core; a shell; a neck removably connected to said core and extending 30 through said shell; and restraining means on

said shell directly cooperating with said neck for locking said neck in position so long as said shell is assembled on said core.

9. A radiator construction comprising, in combination: a core; a shell; a neck removably connected to said core and extending through said shell; means on said neck and means on said shell directly connecting said neck with said shell for locking said neck in position only when said shell is assembled on 40 said core.

10. A radiator construction comprising, in combination: a core; a shell therefor and removable therefrom; a neck removably connected to said core; and means for locking 45 said neck in position when said shell is assembled on said core, said means permitting removal of said neck only upon partial removal of said shell.

11. A radiator construction comprising, in combination: a core; a shell therefor and removable therefrom; a filler neck removably connected to said core; and a connection between said neck and said shell to permit said neck being locked by said shell in one position and removable when the shell is in another position.

In witness whereof I have hereunto set my hand.

WARREN McARTHUR, JR.
